UNITED STATES PATENT OFFICE.

HARRY SHOEMAKER, OF JERSEY CITY, NEW JERSEY.

HYDRO-CONDENSER.

No. 921,014.

Specification of Letters Patent. Patented May 11, 1909.

Application filed July 3, 1908. Serial No. 441,871.

To all whom it may concern:

Be it known that I, HARRY SHOEMAKER, a citizen of the United States, and resident of Jersey City, in the county of Hudson and State of New Jersey, have invented certain new and useful Improvements in Hydro-Condensers, of which the following is a specification.

My invention relates to electrical condensers and more particularly to condensers for use with high potential electric currents, such as used, for example, in wireless telegraph or wireless telephone transmitters, though, of course, useful in connection with low potential circuits.

It is the object of my invention to provide a condenser in which the breakage of the dielectric, due to heating and high potential strains, shall be reduced to a minimum. To this end, I employ conducting liquids or solutions as the armatures of the condenser and glass, preferably, being used for the dielectric, and taking, preferably, the form of a jar or tube.

It has been found heretofore in practice, especially in transmitters of electro-radiant energy, that the coatings in whatever manner applied, were not uniformly applied and with resultant great breakage of the glass or other dielectric. By using liquid armatures, the contact with the dielectric is perfectly and absolutely uniform and continuous and, further, the liquid serves to keep the dielectric cool.

My invention resides in other features for using a plurality of such condensers together to form a large condenser, and to features from which result compactness, security, and efficiency.

My invention resides in other features hereinafter pointed out and claimed.

For an illustration of one of the forms my invention may take, reference is to be had to the accompanying drawings, in which:

Figure 1 is an end view, partly in elevation and partly in vertical section, of my improved condenser, a plurality of condensers being assembled to form a larger condenser. Fig. 2 is a view in elevation, showing means for supporting bus bars on the condenser tank. Fig. 3 is a top plan view of my im-

proved condenser, a portion being shown in horizontal section.

Referring to the drawings, a wooden or other suitable base 1 is surmounted by a wooden or other suitable top 2, upon which are secured or rest a plurality of vertical rods 3, of hard rubber or other highly insulating material, which is, in turn, surmounted by an insulating frame 4, of wood or other suitable material. Carried by the frame 4 is a tank 5 of galvanized iron, or other suitable material. Within the tank are a plurality of vertical rods 6 constituting supports for the upper brass grid 7, and a plurality of shorter brass supports 8 for the lower brass grid 9. A plurality of circular or other openings are formed opposite each other in the upper and lower grids 7 and 9. Through such an opening in the upper grid and the opposed opening in the lower grid extends a metallic basket or container 10 of perforated sheet metal, metal gauze, or non-conducting material, or what not, which rests with its bottom upon the inside of the bottom of the tank 5, which has a flange 11 at its upper end turned horizontally and resting upon the top of the upper grid 7. Into this basket or container is placed a tube or jar 12, of glass or other suitable dielectric material, the same having a closed bottom 13. Suspended in the jar 12 is a tube or rod 14 of brass or other suitable conducting material hung from a conductor 15 of the fork conductor 16 of brass or other suitable conducting material.

A single condenser unit has thus far been described, but a plurality of these units, similarly constructed, are assembled as shown in the drawings. Each conductor fork 16 is shown to have, in this case, four conducting legs or limbs 15.

Upon a bracket 17, Fig. 2, secured to the side of the tank 5 is secured a member 18, of wood or other suitable insulating material, carrying insulator posts 19, of hard rubber or other highly insulating material, and supported upon these insulators 19 are the bus bars 20 extending above the tank 5 and electrically connected to each other, if desired or necessary, by the connectors 21. It is to the bus bars 20 that the conductor forks 16 are mechanically secured and electrically

connected. Thus, all of the tubes or conducting members 14 within the jars or tubes 12 are in electrical communication with each other. When the parts have been so assembled, there is poured into each jar and around the outside of the jars within the tank 5, a suitable conducting liquid or solution, such as a solution of common salt, or of sodium bicarbonate, or, in fact, any suitable substance which will conduct electricity. The nature of the solution will, so long as it is conducting, depend more on the nature of the metals or other conductors with which it comes into contact, it being preferable to use such solutions as will be neutral or practically neutral with respect to such metals or conductors so as to prevent their corrosion or eating away. When the tank and jars have been filled with such a solution or liquid to a suitable height, as for example, to the height of the upper grid 7, or just above the same, there is formed a condenser consisting of a plurality of similar condenser units, the armatures of the condensers being of conducting liquid. The liquid affords an intimate contact with the dielectric or glass of the tubes or jars 12, so that there will be a minimum tendency to localize heating, thus minimizing breakage. Furthermore, the liquid serves to absorb the heat generated in the dielectric or other parts, thus affording a cool running condenser suitable for high potentials, such as employed in wireless telegraphy and the like, and a condenser subject to a minimum of breakage. In case of breakage of a tube or jar 12, the basket or container 10 serves to confine the broken particles and the particular container 10 may be lifted out, after the proper conductor fork 16 has been removed from its bus bar and the glass thrown out and the container replaced and a new jar or tube 12 supplied. The basket or container 10 serves also to conduct current to the liquid immediately in contact with the outside of the jar as does the tube or rod 14 for the liquid within the jar.

While the members 10 and 14 serve, to a degree, as the armatures of each condenser unit, nevertheless it is the liquid armatures which are the most effective ones as is evidenced by the fact that when liquid is absent the electrical capacity of each condenser unit is far different from what it is when the liquid is present.

The terminals of the assembled condensers are, of course, the bus bars 20 and the grids 7 or 9 or the tank 5.

What I claim is:

1. A multiple condenser comprising a tank, a plurality of condenser units contained in said tank and comprising each a jar of dielectric material, conducting liquid

within the jar forming a condenser armature, and conducting liquid contained in said tank and in contact with the outer sides of all said jars to form the second armatures thereof. 65

2. A multiple condenser comprising a tank, a grid therein, a plurality of condenser units supported by said grid, and conducting liquid contained in said tank and forming a common armature of all said condenser units. 70

3. A condenser comprising a fragile dielectric member, conducting liquid forming the armatures of said condenser, and a container immersed in the outer armature and surrounding said dielectric member. 75

4. A condenser comprising a receptacle containing a liquid, a jar of dielectric material surrounded by said liquid, liquid contained within said jar to form the inner armature, and a perforated container surrounding said jar. 80

5. A multiple condenser comprising a tank, a plurality of condenser units contained therein, a mass of liquid in said tank forming the outer armatures of said condenser units, liquid forming the inner armatures of said condenser units, a conductor supported by and insulated from said tank, and electrical connections from said conductor to the inner liquid armatures of said condenser units. 85 90

6. In a condenser, the combination with a receptacle, a grid therein, a container supported by said grid, a dielectric jar within said container, and liquid within and without said jar to form condenser armatures. 95

7. In a multiple condenser, the combination with a tank, of a grid therein, a plurality of containers supported by said grid, dielectric jars within said containers, liquid within said jars to form armatures, and liquid in said tank forming a common armature for all said jars. 100 105

8. In a multiple condenser, the combination with a tank, a plurality of groups of condenser units contained therein, liquid contained in said tank and forming a common armature for all of the units of all groups, an inner liquid armature for each unit, a bus bar for each group of units supported by and insulated from said tank, and connections from each bus bar to the inner armatures of the units of each group. 110 115

9. In a condenser, the combination with a receptacle, a dielectric jar therein, liquid in contact with the inside and outside of said jar to form condenser armatures, and a basket surrounding said jar for confining and removing the pieces of the jar when broken. 120

10. In a condenser, the combination with a receptacle, of upper and lower grids, opposed openings in said grid to receive a con- 125

tainer, a dielectric jar within said container, and liquid within and without said jar to form condenser armatures.

11. In a multiple condenser, the combination with a tank, of upper and lower grids disposed therein, a plurality of dielectric jars supported by said grids, liquid within said tank and in contact with all the jars to form a common armature, liquid within each

jar to form inner condenser armatures, and connections to the inner and outer armatures.

In testimony whereof I have hereunto affixed my signature in the presence of the two subscribing witnesses.

HARRY SHOEMAKER.
